UNITED STATES PATENT OFFICE

HARRY N. STRIEWIG, OF CHICAGO, ILLINOIS, ASSIGNOR TO THE LEHON COMPANY,
A CORPORATION OF ILLINOIS

ROOFING

Application filed July 22, 1926. Serial No. 124,206.

This invention relates to flexible roofing and has for its principal objects to improve the means for fastening the lower or exposed portions of overlapping courses against the 5 tendency of the elements to raise them. In the preferred form here illustrated, this object is obtained by providing the adjacent surfaces of the courses with complementary fasteners which automatically engage when 10 forced together.

In the drawings

Fig. 1 is a plan view of a fragment of roof made with roofing strips embodying the invention;

15 Figs. 2 and 3 are sectional views taken on the lines 2—2 and 3—3 of Fig. 1, respectively; and

20 Figs. 4 and 5 are views similar to Fig. 1 illustrating the application of the invention in connection with roofing strips of different forms.

The roof shown in Fig. 1 is laid upon a suitable deck 10 (Fig. 3) and is composed of strips, each of which includes a body portion 11 and a plurality of rectangular tabs 12 separated by narrow slots 13. Projecting from the lower surface of each tab adjacent to the middle of its lower edge is a yielding element 14 of what is sometimes 25 called a snap fastener. A complementary cup-shaped element 15 of such fastener is carried by the upper face of the body portion 11 adjacent to the upper edge of each slot 13.

In laying the roof, the usual starting strip 35 16 is laid upon the deck 10 adjacent to the eaves and this strip may or may not be provided with the cup-shaped elements 15. The first course of strips is laid upon this starting strip with the tabs even with the eaves.

40 The cup-shaped elements 15 on this course form markers to indicate clearly the position of the next course and it is a very simple matter to place the tabs of the next course and force the projections 14 into engagement

45 with the members 15. A single course of nails 17 is then inserted thru the body portion and into the deck. Each succeeding course is laid in like manner and the comb is finished with a cap in the usual manner.

50 The fasteners, therefore, not only serve to

effectually hold the tabs down, prevent curling or lifting by the wind, ice, etc. but they form very convenient guides to assist the workmen in laying the roof.

In Fig. 4 the strips include a body portion 18 and a plurality of tapered tabs 19 separated by spaces 20 of the same shape and size of the tab whereby the roof is given the appearance of having been made from hexagonal shingles or tiles. With this form of strip, 55 the fastener elements are located adjacent to the middle of the tabs at their lower edges and adjacent to the top of the spacing slots at their upper edges, the lines near the fastener elements corresponding in the complementary shapes of tabs and spacing recesses. Hence by having the cup-shaped members on the body portion adjacent to the top of the recesses and the projecting members on the tabs, the two elements will form markers for 60 locating the successive courses and when 65 pressed together, will securely fasten the ends of the tabs down.

In the form shown in Fig. 5, each strip includes a body portion 21 and a plurality of 75 V-shaped tabs 22 but their lower ends cut away as indicated at 23. The tabs are separated by recesses of complementary shape and include a short line 24 corresponding to the cut away corner 23. The complementary 80 fastener elements are carried adjacent to these short lines and perform the functions described above.

The fasteners shown can be readily made and inserted in the roofing strips by automatic machinery during the manufacture of the strips or as a separate operation. The snap fastener here shown is the preferred construction but it is obvious a variety of other forms can be used without departing 85 from the spirit of the invention, and it is, therefore, intended that such forms shall be included in the following claims.

I claim as my invention:

1. A roof comprising a deck and a plurality 95 of overlapping courses of flexible roofing material, each course including a lower exposed weather portion overlapping an upper portion of a course below, and a snap fastener for securing the exposed weather portion to 100

the overlapped portion of the course immediately below and including two elements, one carried by the underside of the overlapping portion and one carried by the upper side of the overlapped portion and arranged in staggered relation with respect to the other.

5 2. Flexible roofing in strip form comprising a body portion and a plurality of spaced tabs projecting from one side of the body portion, snap fastener elements carried by the upper side of the body portion in alignment with the spaces between the tabs and complementary snap fastener elements carried by the underside of each tab adjacent to the middle thereof.

10 3. Flexible roofing in strip form comprising a body portion and a plurality of spaced tabs projecting from one side of the body portion, snap fastener elements carried by the upper side of the body portion in alignment with and adjacent the spaces between the tabs and complementary snap fastener elements carried by the under side of each tab adjacent to the middle thereof and adapted 15 to secure itself to the fastener element carried by the upper side of the body portion when pressed together in a downward direction.

20 4. A roof comprising a deck and a plurality of overlapping courses of flexible roofing material, each course comprising a body portion and a lower exposed weather portion including a plurality of spaced tabs, said tabs overlapping the body portion of a course below, and a snap fastener for securing the tabs to the body portion of the course immediately 25 below, and including two elements, one carried by the tabs and one carried by the overlapped body portion.

25 40 In testimony whereof I affix my signature.

HARRY N. STRIEWIG.
